UNITED STATES PATENT OFFICE.

LOUIS HOFFMAN, OF DULUTH, MINNESOTA, ASSIGNEE, BY MESNE ASSIGNMENTS, TO
STEAM PRESSING IRON COMPANY, A CORPORATION OF DELAWARE.

PRESSING IMPLEMENT.

Application filed March 1, 1920. Serial No. 362,624.

To all whom it may concern:

Be it known that I, LOUIS HOFFMAN, a citizen of the United States, residing at Duluth, in the county of St. Louis and State of Minnesota, have invented certain new and useful Improvements in Pressing Implements, of which the following is a specification.

My invention relates to the manufacture of implements for moistening and pressing clothing and cloth goods, or the like, and more especially to the manufacture of a sad iron or tailor's goose intended to be continuously heated and to inject moisture in the form of steam against the goods or garment being pressed (obviating the necessity of sponging or sprinkling such goods or garment), an implement of this type being either supplied with water, which is generated into steam and heated to the temperature desired by means of a heating element associated with said implement, or being supplied with steam which, if a separate heating element is used, such as a gas burner, for example, will be dried and superheated in passing through the body of the implement to the pressing surface thereof.

One of the principal objects of the invention is to provide a novel pressing and moistening implement of this general character which may be conveniently and cheaply manufactured, and a new and useful method of manufacturing the same.

A further object is to provide a moistening and pressing implement of the character described which will be composed in part or wholly of a metal or metals having a coefficient of thermal conductivity considerably higher than that of cast iron of which flat irons and the like have usually been made, whereby the efficiency of the implement is increased, more especially when moisture is supplied in the form of water to be generated into steam in the body of the device. In this respect the invention of the present application is an improvement upon the pressing implement described and claimed, more generically so far as regards this feature, in my co-pending application Serial No. 343,409, filed December 8, 1919.

The invention is illustrated in a preferred embodiment, susceptible, however, of very considerable modification, as will be

apparent, in the accompanying drawings wherein

Fig. 1 is a vertical sectional view of a tailor's goose of the moistening, self heated type, constructed in accordance with the 60 principles of my invention.

Fig. 2 is a fragmentary inverted plan view of the implement.

Fig. 3 is a view, in perspective, of certain parts of the implement to illustrate particularly the improved method of manufacturing the same, and

Fig. 4 is a sectional view on line 4—4 of Fig. 1, omitting the burner.

Like characters of reference designate 70 like parts in the several figures of the drawings.

Referring to the drawings, the body of the sad iron or tailor's goose is composed of a cast metal, hollow core 10, a pipe coil 11 75 and a body of cast metal 12 in which the core and coil are embedded. The coil has an extended portion 13 lying between the core and the pressing surface 14 of the implement, this part of the coil being preferably bent and disposed as best shown in Figs. 2 and 3 so as to distribute moisture in the form of steam, generated or superheated in the coil, to a considerable number of different points on the pressing 85 surface, through perforations 15. The lower end of the coil is closed by means of a screw plug 16, for example, and the upper end is set into a valve casing 17, the duct 18 of which communicates with the 90 coil and is controlled by a valve 19. This valve is shown as a rotary valve threaded through an annular member 20 fixed within the casing 17 and is provided with an operating lever 21 having a finger piece 22 95 for convenience in manipulating it. A packing 23 is interposed between the annular member 20 and packing nut 24. 25 is a pipe to which a flexible tube (not shown) may be connected for conducting water or 100 steam to the valve casing 17. A plate 26 is secured to the top of the body of the implement by means of screws 27 and the support 28 for the handle 29 is secured to the plate by screws 30. Insulating material 31 is placed between the plate 26 and the body of the implement. These details of construction of the valve and handle form no part of my present invention. If 105 the implement is supplied with steam at 110

relatively high temperature it will not be necessary to furnish the implement with separate heating means. Where it is desirable to eject dry or superheated steam against the goods a heater will be used; and some sort of heating element is, of course, necessary where the moistening medium is supplied to the iron in the form of water. Any suitable heating device might be employed in this connection. I have shown a burner 32 secured to the iron by a screw 32^a which projects into a space or heating chamber 33 within core 10, which is made hollow, through an opening in the hinged door 33^b with which the device is preferably furnished.

The pipe coil 11 is preferably made of some metal having a relatively high coefficient of thermal conductivity and which will be sufficiently pliable to allow it to be bent to the extent required. Preferably I employ copper tubing for this purpose. The core 10 and the body of the implement 12 are composed preferably of aluminum or aluminum alloyed with copper. There is a great advantage in making the implement of these metals both of which transmit heat rapidly; and this is particularly so where the moistening medium is supplied in the form of water. It has been found very difficult in practice to provide a cast iron tailor's goose or sad iron of the moistening type which can be successfully used when supplied with water to be generated into steam in the iron. The flow of water through the water duct of the iron cools the metal surfaces with which it comes into contact so that either the water will not flash into steam, after the device has been in operation for a short time, or the vaporization is not complete so that the goods are moistened to too great an extent and the moistening fluid applied at too low a temperature. The higher the temperature of the moisture applied to the goods and the smaller the amount of moisture in excess of that actually required for softening the goods sufficiently to remove wrinkles (in most pressing operations with ordinary irons the moisture is greatly in excess of what is required) the more quickly and easier will the pressing operation be performed. By having the moisture duct of a pressing implement of this type composed of copper, or other metal having a high coefficient of thermal conductivity the cooling of the walls of the duct by the contact of the continuously supplied, relatively cold water will be minimized, particularly if the body of the implement be also composed of metal, such as aluminum, for example, which also has a high coefficient of thermal conductivity. With the implement so made a rapid equalization takes place as between the parts of the device more and less af-

fected by the cooling influence of the water which makes it possible to generate and deliver relatively dry steam to the pressing surface of the implement and which minimizes the danger of scorching the goods by application of too much heat to the base of the implement.

The method of making the device above described is as follows: The hollow core 10 is first formed by casting, preferably. The core is preferably formed with a spiral corrugation and the copper tubing is coiled around the outside of the core in the groove provided by the corrugated configuration of the outer surface and the valve casing 17 set on or fitted to its upper extremity, the lower portion being bent so as to form a substantially horizontally disposed coil 13 below the core 10. The parts as thus assembled (as shown in Fig. 3) are placed in a suitable mold, preferably a metal chill, and the body portion 12 of the implement is formed by casting molten aluminum around them. During the casting cold water is preferably run through the coil to prevent it from being melted, the lower end of the coil being left open and registering with an outlet opening in the mold. When this operation is completed the bottom surface of the implement may be machined or otherwise smoothed, the perforations 15 drilled through the base portion of the implement and the adjoining portion 13 of the pipe coil and the lower end of the coil closed by plug 16. The other parts of the device are then assembled in a manner which will be obvious.

I claim:

1. A moistening and pressing implement comprising, in combination, a metal core, tubing surrounding said core, and a body of cast metal in which said core and tubing are embedded, said tubing being provided with a discharge opening to direct moisture to the material being pressed.

2. A moistening and pressing implement comprising, in combination, a metal core, a pipe, providing a moisture duct, coiled around said core and having an extension below the same, and a body of cast metal in which said core and pipe are embedded, said extension being provided with a discharge opening to direct moisture to the material being pressed.

3. A moistening and pressing implement comprising, in combination, a metal core, a pipe, providing a moisture duct, coiled around said core and having an extension below the same, and a body of cast metal in which said core and pipe are embedded and which provides a pressing surface, said body of cast metal and the extension of said pipe being formed with aligning perforations for conducting moisture to said pressing surface.

4. A moistening and pressing implement comprising, in combination, a metal core, tubing surrounding said core, and a body of cast metal in which said core and tubing are embedded, which provides a pressing surface, said body and tubing being pierced to conduct moisture to said surface.

5. A moistening and pressing implement comprising, in combination, a metal core formed with a heating chamber, tubing surrounding said core, a body of cast metal in which said core and tubing are embedded and which provides a heat distributing member of the implement, and a heating element arranged in said heating chamber; said tubing and body being pierced to conduct moisture to the material being pressed.

6. A moistening and pressing implement comprising, in combination, a metal core, a pipe coil surrounding said core, a valve casing arranged at one end of and communicating with the pipe coil, and a body of cast metal in which said pipe coil and a portion of said valve casing are embedded.

7. A tailor's goose comprising, in combination, a core, metal tubing coiled around the core and extending back and forth under the core, and a body of cast metal in which said core and tubing are embedded, said body and tubing being perforated for conducting moisture to the pressing surface of the implement.

LOUIS HOFFMAN.
